UNITED STATES PATENT OFFICE.

JUSTIN W. HEILBRON, OF NEW YORK, N. Y.

SUSPENDERS.

No. 799,464.

Specification of Letters Patent.

Patented Sept. 12, 1905.

Application filed February 17, 1905. Serial No. 246,043.

To all whom it may concern:

Be it known that I, JUSTIN W. HEILBRON, a citizen of the United States, residing at New York, in the county of New York and State of New York, have invented certain new and useful Improvements in Suspenders, of which the following is a specification, such as will enable those skilled in the art to which it appertains to make and use the same.

My invention relates to suspenders, braces, and the like, and more particularly to means for adjusting the lengths of the front end portions of the webs or straps of devices of this class from which the attaching devices by which connection is made with the trousers and undergarments are suspended; and the object of the invention is to provide improved means for accomplishing the said adjustment and also for suspending the trousers and undergarments or for attaching the devices by which the trousers and undergarments or drawers are suspended.

The invention is fully disclosed in the following specification, of which the accompanying drawings form a part, in which the separate parts of my improvement are designated by suitable reference characters in each of the views, and in which—

Figure 1 is a perspective view of the front end portion of one of the webs or straps of a pair of suspenders provided with my improvement; Fig. 2, a longitudinal central section thereof; and Fig. 3, a view similar to Fig. 2, but showing a modification.

In the drawings forming part of this specification I have shown at *a* the front end portion of one of the webs or straps of a pair of suspenders, and in the practice of my invention I provide a slide *b*, through which the web

or strap *a* is passed in the direction of the arrow *x* in Fig. 1, and said slide in the form of construction shown consists simply of a link or loop the outer side of which is provided with a clamp *b*², similar to the clamps of other devices of this class, said clamp being provided with a projecting tongue portion *b*³ and with backwardly-directed teeth at *b*⁴, and the tongue portion *b*³ of the clamp *b*² is preferably provided with a tab *b*⁵. I also provide

in the form of construction shown in Figs. 1 and 2 a supplemental slide *c*, through which the web or strap *a* is also passed and which in the form of construction shown consists of an oblong link, and after passing the web or strap through the supplemental slide *c* the end thereof is carried backwardly and upwardly

and again passed through the slide *b*, as shown at *b*⁶, and the free end *a*² of the web or strap *a* is suspended from the slide *b* and is provided at its lower end with an attaching-clip or similar device *d*, from which is suspended a flexible support *d*², having a spring-clamp *d*³, which is designed to be connected with the drawers at the front thereof and to support the same. The supplemental slide *c* is also provided with a tab-attaching device *e*, having a loop *e*², through which is passed a trousers-suspending strap or similar device *f*, and the strap or similar device *f* is provided with buttonholes *f*², whereby connection is made with the buttons at the front part of the waistband of a pair of trousers. As thus constructed it will be seen that the end *a*² of the web or strap *a* is free to move through the slide *b*, but the clamp *b*² or the teeth thereof when in operation not only hold the web or strap *a*, but also hold the end *a*² of said strap or web, and in order to easily move the end *a*² of the web or strap *a* through the slide *b* the tongue *b*³ of the clamp *b*² must be raised and turned upwardly, and at this time the slide *b* may be pulled upwardly on the web or strap *a* or lowered on said web or strap, and the length of the depending loop-shaped portion *a*³ of said web or strap may thus be adjusted as desired, as may also the length of the end portion *a*² of said web or strap. It will therefore be seen that with this construction I provide a simple and convenient means for adjusting the position of both of the suspending-device attachments or holders *d*² and *f*, and it will also be apparent that the suspending device or holder *d*² may or may not be employed or used, according to the desire of the party wearing the suspenders.

In the modification shown in Fig. 3 the supplemental slide *c* is provided with a backwardly-directed supplemental loop-shaped member *c*², through which the end *a*² of the web or strap *a* is loosely passed, and this serves to hold the end *a*² of the web or strap *a* in proper position at all times whether the suspending strap or support *d*² be employed or not, and with both forms of construction it will be seen that the end *a*² of the web or strap *a* is free, or, in other words, is in no way attached except when in use for the purpose of suspending the drawers. It will also be apparent that the slide *b* or that portion of which over which the end *a*² of the web or strap *a* is passed may be provided with a roller, if desired, as may also that portion of

the slide *c* around which the loop-shaped portion *a*³ of the web or strap *a* passes; but these rollers are only for the purpose of reducing friction and may or may not be employed.

5 Although I have shown the front end portion of but one of the webs or straps of a pair of suspenders, it will be apparent that both of said webs or straps are similarly formed or provided, and my invention is applicable 10 to suspenders of all kinds or classes regardless of the material of which they are composed, and it will also be apparent that my improvement may be applied to belts, garters, and similar devices.

15 Having fully described my invention, what I claim as new, and desire to secure by Letters Patent, is—

1. In a device of the class described, a web or strap, a main slide mounted thereon and 20 free to move thereon and provided with a front clamp, and a supplemental slide below the first-named slide and through which said web or strap is passed, said supplemental slide being provided with a tab-attaching 25 device, and the end portion of the web or strap after being passed through the supplemental slide being carried upwardly to the main slide and passed backwardly therethrough and sus-

pended therefrom and provided with an attaching device, substantially as shown and described. 30

2. In a device of the class described, a web or strap, a main slide mounted thereon and free to move thereon and provided with a front clamp, and a supplemental slide below 35 the first-named slide and through which said web or strap is passed, said supplemental slide being provided with a tab-attaching device, and the end portion of the web or strap after being passed through the supplemental 40 slide being carried upwardly to the main slide and passed backwardly therethrough and suspended therefrom and provided with an attaching device, said end portion of the web or strap being also again passed loosely through 45 the supplemental slide, substantially as shown and described.

In testimony that I claim the foregoing as my invention I have signed my name, in presence of the subscribing witnesses, this 15th 50 day of February, 1905.

JUSTIN W. HEILBRON.
